Remington Arms Company, Inc., a corporation
of Delaware

Original application March 4, 1939, Serial No.
259,842. Divided and this application April 8,
1941, Serial No. 387,405

2 Claims. (Cl. 29—1.23)

This invention relates to projectiles and more particularly to the method of making jackets for projectiles.

The present application is a division of my prior co-pending application, Serial No. 259,842, filed March 4, 1939, now Patent No. 2,321,344, issued June 8, 1943.

As explained in the aforesaid application, with the advent of smokeless powders and increase in velocities, the use of lead projectiles, particularly for their mushrooming characteristics, became impossible because the lead was stripped by engagement with the rifling in the barrel. This caused inaccurate flight due to the absence of rotary motion and also severely fouled the bore of the weapon.

To overcome this objection, bullets with a hard metal jacket were used but as the velocities of bullets were continually increased it was found that the jacket material would separate from the core upon impact. As the jacket material did not have sufficient inertia it would stop and the core material would then disintegrate and not penetrate the target to give the desired effect and would also scatter portions of the metal through the edible meat.

It is the object of this invention to provide a means of manufacturing a suitable jacket to give the desired core locking qualities so that the projectile core will not separate from the jacket upon impact.

In the drawing:

Figs. 1 to 6, inclusive, are successive views showing a jacket blank and its behavior as a punch and die operate thereon.

Fig. 7 is a fragmentary view of a modified punch.

Fig. 8 is a sectional view of a punch of the general shape shown in Fig. 7 and its die.

In accordance with the object of this invention it is proposed to construct a jacket with walls of reduced thickness near the base portion so as to form a widened interior portion and yet maintain the exterior walls of the jacket of substantially continuous symmetry throughout their entire length. The widened interior portion of the jacket permits a core to be locked in the jacket and held from separation therefrom on impact of the bullet.

In the process of manufacture of projectile jackets on a mass production basis, it is evident that some simple and efficient means must be employed to secure the widened portion near the base of the jacket. This prohibits the use

of an expanding punch or other and more complicated tools.

By way of example, in Figs. 1 to 6, inclusive, I have illustrated one method by which the cup and jacket may be formed by use of a punch and die. I have found that the metal blank used should be of substantially the desired finished thickness of the major wall portion of the jacket and that this thickness should not be substantially reduced during subsequent forming operations.

In Figs. 1 to 6, inclusive, the blank is at 28, the punch at 29 and one form of die at 30. The punch in Fig. 1 has just started to contact the blank 28 which has been placed into position on the die 30. As the punch moves inward (Fig. 2) force is exerted against the blank 28, causing it to start to assume a cup shape. The force of the punch commences to strain the metal adjacent the circumference of the punch which is evidenced by the fact that if a sharp edge punch be used instead of the rounded shoulder punch of 29, the punch will go completely through the blank without substantially bending the same. In Fig. 3, the punch has progressed further and the circular section 31 adjacent the outside of the punch has started to thin out, which is shown in exaggerated form in the drawing. As the punch progresses still further (Fig. 4), the blank is puckered at the outside edge which gives increased resistance to its passage through the die and consequently a greater thinning out of the metal at 31. Then as the sides of the cup are folded in and become circular in shape (Fig. 5) and as the thickness of the wall has not been reduced, the wall at 31 (see Fig. 5) will not be forced against the punch and there will be a widened portion in the interior at this thinned out portion. The upper portion of the cup, not having been thinned out, will completely fill the space between the punch 29 and the wall 32 of the die which is substantially the same as the thickness of the original metal. Fig. 6 shows the cup just before it is stripped from the punch after passing completely through the die.

The subsequent forming operation may consist of reduction of the diameter in successive punch and die processes, in which the clearances 50 are maintained the same as the finished wall thickness similar to that in the formation of the cup. Further thinning out will take place at 31 as the jacket is passed through each smaller die and the thinned portion will be moved further up the wall at each forming because

the section immediately adjacent the outside of the punch on or near the bottom of the cup is squeezed to the side wall of the cup as the piece is forced downward in the contracting portion of the die in the same way as that illustrated in Figs. 1 to 6. It is therefore seen that the widened out portion is thinned out more in each operation and is increased in extent. This thinning out is further increased by stretching as the cup is further passed through the die due to the resistance to this passage as the upper part is squeezed into a smaller diameter and the absence of metal to fill the thinned portion due to the major wall thickness having been maintained the same.

A modified punch is illustrated in Fig. 7 which, instead of having a slightly rounded corner, has a plurality of progressively decreasing concentric shoulders 36. The punch is used in a manner similar to that shown in Figs. 1 to 6 and the die assumes the same general shape, although the profile 35 may be a little sharper as shown in Fig. 8. The indentations weaken and extend the metal between the shoulders and cause a larger widened portion. The indentations also form a further locking action between the core and the jacket. The use of this type of punch also allows the subsequent forming operations to be reduced. In the modification of Figs. 1 to 6, usually four drawing or closing-in operations are necessary whereas with the modification of Fig. 7 only three are necessary. This is due to the fact that the indentations produced by the shoulders at the bottom of the cup serve as a centering means for the next punch, thus insuring walls of uniform circular thickness which would not be the case if the substantially smaller punch should engage the die off-center.

I have by my method produced a jacket of superior core-locking qualities. The core-locking means whereby the core is held in position in the jacket so that they will not separate upon impact solves a problem existent with previous forms of bullets. This method of making the widened portion of the interior of the jacket, one form of which is herein disclosed, provides a cheap and efficient means adaptable to modern quantity production methods.

The method may also be used in the formation

of metallic cups or containers for any use in which it is desirable to place a filler in locking relationship therewith.

The process of forming the jackets may also be applied to blanks of cup shape, the cup being of the substantially desired finished wall thickness.

What is claimed is:

1. In making a metallic cup bullet jacket having an interior side wall portion adjacent to the base which is of greater diameter than an interior side wall portion removed from the base, the method which comprises providing a flat blank of a thickness substantially equal to the desired thickness of the major portion of the finished cup; indenting and weakening a portion of the blank which will form the interior side wall of said cup adjacent the base by using a punch with a sharp shoulder; and then forming said blank into a cup, by passing through a die and punch having a clearance substantially the same as the wall thickness of the major portion of the cup, by stretching and thinning said weakened portion adjacent said base only and maintaining the major part of said wall a thickness substantially the same as that of the blank.
2. In making a metallic cup bullet jacket having an interior side wall portion adjacent to the base, substantially all of said interior side wall portion being of greater diameter than the interior side wall portion removed from the base, the method which comprises providing a flat blank of a thickness substantially equal to the desired thickness of the major portion of the finished cup; weakening a portion of the flat blank which will form the interior side wall of said cup with a plurality of peripheral indentations by applying thereto a punch having a plurality of sharp shoulders; and then forming said blank into a cup, by passing through a die and punch having a clearance substantially the same as the wall thickness of the major portion of the cup, by stretching and thinning said weakened portion adjacent said base only and maintaining the major part of said wall a thickness substantially the same as that of the blank.
